H. S. MELLOTT

CONCENTRATOR

Filed Feb. 4, 1921

UNITED STATES PATENT OFFICE.

HOWARD S. MELLOTT, OF MORENCI, MICHIGAN.

CONCENTRATOR.

Application filed February 4, 1921. Serial No. 442,383.

To all whom it may concern:

Be it known that I, HOWARD S. MELLOTT, a citizen of the United States of America, residing at Morenci, Lenawee County, Michigan, have invented new and useful Concentrators, of which the following is a specification.

This invention relates to flowing or impelling treatment of substances, especially in 10 heat transference operations.

This invention has utility as a centrifugal evaporator more particularly for film treatment of milk.

Referring to the drawings:

15 Fig. 1 is a side elevation with parts broken away of an embodiment of the invention in a centrifugal evaporator;

Fig. 2 is an end view with parts broken away; and

20 Fig. 3 is an enlarged detail section of the apparatus of Fig. 1, at the discharge.

From the idle pulley 1 belt 2 may be shifted to fast pulley 3 driving shaft 4 extending through the evaporator or heat exchange apparatus having head 5 at one end and head 6 at the other. Between these 25 heads is a cylindrical member having inner smooth wall 7. This cylindrical member extending between the heads 5, 6, and having the inner smooth wall 7, on its outer side has a roughened or uneven surface 8. The side 7 of this member is the outer wall of the inner chamber, while the side 8 is the inner wall of an outer chamber herein 30 enveloping the inner chamber as a steam jacket. The outer wall of this outer chamber is a cylindrical member 9 to which chamber steam or other heating substance may be supplied through a plurality of 35 openings 10. In the instance where this substance supplied is steam for flowing over the roughened surface 8 of the partition member, such steam may condense or flow off as controlled by a valve 11 through a 40 pipe 12.

Shaft 4 is shown as provided with a hub 13 carrying arms 14 carrying pivoted blades 15 shown as of thin or flexible material which in operation may be centrifugally 45 thrown into sliding contact against the smooth partition wall 7. These blades or impellers 15 are shown as having notches 16 in the outer edges and series of openings 17, 18, therethrough.

50 With the apparatus at rest, stops 19 are

provided for the swingable blades so that upon starting the apparatus which may be operated at a speed of 400 revolutions per minute in a machine three feet in diameter and say three feet long, these blades 60 may be in position to be readily thrown out into normal riding relation as to the interior of the smooth vessel or partition wall. The substance to be treated, as a flowing material, may be considered as milk, 65 warmed to a pre-determined temperature, say in the range of 190° F., to enter by line 20 and pass by way of slot 21 (Fig. 2) to be drawn therefrom by the ends of moving blades 15 and thrown out against the 70 cylinder 7 at a supply rate determined by valve 22. This slot 21 is shown as spaced but a slight distance from the cylindrical surface 7, say in a thirty-six inch diameter machine, about one inch therefrom. The 75 speed of operation is such that this material is at once thrown as a thin sheet or film about the interior of the wall 7. The blades or impellers 15 seem to have a fanning action as well as a dispersing action 80 and the material is free to flow during this high speed of revolution of the impellers 15, and this flow is toward the remote or opposite head 6 of the apparatus from which it may escape by elongated opening 23 85 flush with the surface 7 into duct for pipe 24. Accordingly, there is no head resisting discharge of the treated material.

In practice a vessel three feet in diameter and three feet long may readily handle as 90 low a volume as two quarts, or less, in the machine. The speed of operation as indicated is gaged to urge the material to change its position as to the wall 7 at such a rate that the capacity for delivering heat 95 by this copper or good conductor wall or partition may be at a maximum. The capacity per unit of area for this smooth portion of the partition is thus directly mechanically controlled. The conductivity of this 100 partition having the surfaces 7, 8, is very considerable when the material is of copper.

Notwithstanding there is a pressure in the steam jacket say of fifty to seventy-five pounds, the capacity per unit of area for extracting this heat from the steam and getting it through this partition 8, 7, is increased. To this end, this partition has the roughened 105 surface 8 increasing the capacity of this 110

partition for lowering the temperature of the steam or other substance in the jacket and accordingly increasing the rate of heat transference from the jacket to the surface 5 7. This great rate of heat travel through this partition built up on the outside by the surface area increase and built up on the inside by the speed for shifting the material, means a great capacity per unit area of 10 this apparatus, which may run for milk, upward of two hundred pounds per square foot per hour with one quart in the machine and accordingly the interval of treatment being as brief as four seconds. 15 At once upon the milk in this chamber being subjected to this heat treatment, it fluff's up with bubbles, but such bubbles due to their less specific gravity are so consistently dispersed by the spring metal impellers 15 20 that the heavier particles of material are continually so thrown that the wall 7 is bombarded therewith by a condensed liquid or semi-liquid having almost instantaneous transformation to partial gas, such gas of 25 lighter specific gravity escaping from the bubbles as the collapsed bubble walls then move toward the surface 7.

From this interior of the vessel 7, such escaping vapors may pass through the open 30 end 5 by way of shaft 25 to be thrown off by the stack height or by fan, as may be desirable. The proportion of water remov-

ed may be such as to condense the milk from three volume to one volume, or even less.

What is claimed and it is desired to secure by United States Letters Patent is:—

1. In a heat transference apparatus, a cylindrical chamber having a head, impelling means in the chamber, a jacket for the chamber, a supply way embodying a pipe, and a slot terminus for the pipe spaced from the cylindrical portion of the chamber in said head to preclude back action thereinto by the impelling means and extending in the direction of the impelling means travel 40 to a coat for withdrawal of material from the pipe.

2. A heat transference apparatus embodying a horizontal cylindrical chamber having a head, and an infake opening of slot form 50 in the head spaced from the cylindrical portion of the chamber to interpose resistance against back flow therewith, a second head, and an outlet in the second head flush with the cylindrical portion of the chamber for 55 ready discharge flow therefrom.

3. A heat transference apparatus embodying a cylindrical chamber, means for impelling substance therein continuously as a tubular layer, and a steam jacket for the chamber, said chamber having a sheet metal wall corrugated on the jacket side thereof only.

In witness whereof I affix my signature.
HOWARD S. MELLOTT.
